T. L. CROOM

CAN OPENER

Filed Aug. 30, 1921

INVENTOR:

THOMAS L. CROOM,
By: Oscar H. Kueger,
his Atty.

UNITED STATES PATENT OFFICE.

THOMAS L. CROOM, OF LOS ANGELES, CALIFORNIA, ASSIGNOR OF ONE-HALF TO C. C. HENRY, OF LOS ANGELES, CALIFORNIA.

CAN OPENER.

Application filed August 30, 1921. Serial No. 496,841.

To all whom it may concern:

Be it known that I, THOMAS L. CROOM, a citizen of the United States, residing at Los Angeles, in the county of Los Angeles and State of California, have invented a new and useful Can Opener, of which the following is a specification.

This invention relates to devices for opening cans made of sheet metal.

10 One of the objects of this invention is to provide a cutting member pivotally connected to a handle.

Another object is to provide a cutting member with a cutting edge projecting sideways from one of the flat sides of the cutting member and providing the flat body portion of the cutting member with an aperture for a pivot connection to support the cutting member swingably in a plane parallel to the 20 flat sides of the cutting member.

Another object is to provide a pivotally connected cutting member with a handle, the edges of the pivotally connected end of the handle being roughened or knurled cross-wise to the swinging movement of the cutting member in relation to the handle.

Another object is to design a device of this type to be manufactured at a low cost but durable.

30 Another object is to provide a device in which the cutting member may easily be exchanged.

Other objects will appear from the following description and appended claim as well as from the accompanying drawing, in which—

Fig. 1 is a top plan view of the device in the simplest form.

40 Fig. 2 is a front elevation of the device as illustrated in Fig. 1.

Fig. 3 is a section through the handle portion on line 3—3 of Fig. 2.

45 Fig. 4 is a section through the pivot connection of the handle and cutting member, in a slightly modified form, extra knurled washers being inserted between the handle and the cutting member.

Fig. 5 is a top plan view of one of the knurled washers.

50 Fig. 6 is a view similar to the illustration in Fig. 4 of a still more slightly modified form.

Fig. 7 is a top plan view of the pivot end of the handle of a slightly modified form to

be used in connection with the knurled washers.

Can openers are normally punched into the top of a can near the edge and then operated to sever a suitable portion of the top from the can.

In Figs. 1 and 2, the cutting blade 8 is formed and provided to be punched into the material of a can. This cutting blade 8 projects sideways from the main body 9 of the cutting member. The cutting member 65 is pivotally engaged at 10 with the end 11 of the handle 12. The handle is preferably made of sheet metal, so that two halves may be placed together to form a smooth outside. The opposing edges of the halves near 70 the end 11 are reduced in height, as indicated at 13 in Fig. 2, to form a space for the cutting member for swingably engaging between the halves of the handle in the end 11. A screw 14 is illustrated to connect 75 the halves of the handle in the free end of the handle.

For cutting or opening a can, the cutting member of this device is inserted into the cover or top of the can near the edge so 80 that the cutting edge of the blade 8 points in the direction along the edge of the can. The handle 12 is then moved and pressed in the direction of the arrow 15 towards the can. A pressing of the free end of the 85 handle 12 in the direction of the arrow 15 causes also a pressing of the end 11 of the handle against the edge of the can. The edges 16 of the end 11 are preferably roughened or toothed so as to engage with the edge 90 of the can when so pressed against the can. The friction between the roughened edges 16 of the end 11 of the handle 12 is sufficient to draw the cutting member along the edge of the can thereby cutting and opening 95 the can. On moving and swinging the free end of the handle in the direction of the arrow 17, that is, away from the can, the end 11 of the handle is normally also moved away from the edge of the can thereby freeing the roughened edges 16 from the edge 100 of the can so that the free end of the handle can be swung in the direction of the arrow 17 without any resistance. As soon as the movement of the handle is reversed, however, to move in the direction of the arrow 15 towards the can, the edges 16 again engage with the edge of the can, so that the

105

edges 16 practically roll along the outside of the edge of the can while the cutting blade 8 is forced to cut through the top along the edge of the can.

5 Being of sheet metal, the handle is preferably recessed, as indicated at 18 in Figs. 2 and 3, so that the screws do not project beyond the contour of the handle.

Instead of roughening the end 11 of the 10 handle, roughened or knurled washers 19 are placed between the halves in the end 11 in the slightly modified forms illustrated in Figs. 4 and 6.

A washer 19 is illustrated in detail in Fig. 15 5, having the roughened, knurled, or toothed edges 20. A pin 21 is indicated to be engaged with the handle end 11 so as to prevent the washer from turning within the handle end. The engaging means may, of 20 course, be reversed, so as to show a perforation in the washer to engage with a suitable piece or member on the handle end.

In Fig. 7, the handle end 11 is provided with a number of perforations 22, so as to 25 allow a changing of the washers in relation to the handle end 11, which is of advantage since the washers are normally only used a short distance at a time, according to the swinging movement of the handle.

30 The impressions 18 in the free end of the handle are illustrated so that the inner faces of the halves touch, so as to make a spot-welding of the handle at this point possible.

In Fig. 6, impressions 23 are illustrated near the end 11 sidewise of the washers so as to also make a spot-welding of the handle possible at the end 11. The handle end 11 is in this case provided with the double-shouldered pivot 24 instead of the screw. 35

From the above it will be understood that 40 I do not limit myself to any specific design or construction and that the device may be slightly modified in various ways without departing from the principles disclosed by this invention in the foregoing specification 45 and appended claim.

Having thus described my invention, I claim:

In a can opener, a handle member made 50 of sheet metal having its longitudinal edges and narrower terminations rolled in so as to meet the edges of a second similarly stamped member, the endwise facing surface of the material of the rolled-in edges in one termination being roughened in the stamping to form engaging teeth of a width greater than the thickness of the material in the 55 assembled can opener.

In testimony that I claim the foregoing 60 as my invention I have signed my name in the presence of two subscribing witnesses.

THOMAS L. CROOM.

Witnesses:

O. H. KRUEGER,
JESSIE A. MANOCK.
